UNITED STATES PATENT OFFICE.

GERARD C. SCOTT, OF COLUMBUS, OHIO.

SIDEHILL BUILDING CONSTRUCTION.

SPECIFICATION forming part of Letters Patent No. 726,998, dated May 5, 1903.

Application filed July 14, 1902. Serial No. 115,582. (No model.)

To all whom it may concern:

Be it known that I, GERARD C. SCOTT, a citizen of the United States, residing at Columbus, in the county of Franklin and State of Ohio, have invented a certain new and useful Improvement in Sidehill Building Construction, of which the following is a specification.

My invention relates to the improvement of sidehill or inclined building construction; and the objects of my invention are to provide an improved building construction adapted for location on a hillside, to so construct my improved building as to provide a comparatively large area of floor-space by the utilization of a comparatively small area of ground, to provide a hillside or inclined building with a plurality of compartments arranged on different planes, each compartment having means for the entrance of light and means for gaining access to the compartment, and to otherwise produce an improved building construction whereby the surface of a sidehill may be profitably utilized. These objects I accomplish in the manner illustrated in the accompanying drawings, in which—

Figure 1 is a view in perspective of a portion of my improved building, showing the hill upon which the same is located partly in section and showing one end of the building partly removed; and Fig. 2 is a similar end view of a building with the end covering removed, showing a slightly-modified construction.

Similar numerals refer to similar parts throughout both views.

In carrying out my invention I support upon the level or approximately level ground at the foot or base of a hill a horizontally-disposed lower compartment or ground-floor 1, from which rises and extends through the length of the building the forward vertical wall 2. Rising from the rear of the floor 1 is a vertical rear wall 3, this wall having arranged therein at intervals throughout its length vertical frame posts or standards 4, which rise to a greater height than the height of said rear and front walls 3 and 2, which may be equal. Rising from steps or ledges formed in the hillside, one above the other and in rear of each other, are vertical walls

5, corresponding with the lower wall 3, these walls 5 being of corresponding heights from their bases to their tops, and therefore, owing to their being supported at different heights, 55 caused to extend successively one above the other. As described for the wall 3, the walls 5 are provided at suitable intervals with supporting standards or posts, such as are indicated at 6 in the drawings. From the base 60 of each of the walls 5 extends forward or outward horizontally a floor 7, which meets or abuts against the wall 5 or 3 immediately in front thereof, thus resulting in the formation of a plurality of elongated passages 65 or hallways 8, which are arranged vertically on an inclined plane. From the upper side of each of the walls 3 and 5 extends horizontally forward a floor, these floors being indicated at 9. At their forward ends the floors 70 9 are provided with upwardly-projecting and outwardly-inclined wall-like extensions 10. The floors 9 may be supported by inclined frame pieces or braces 11, connecting the framework of the floors with the vertical 75 wall-posts, or said floors may be otherwise suitably supported by standards interposed between them. The upper rear wall of the structure is provided with a forwardly-extending roof or cover 12, and from the forward edge portion of this roof or cover extends downward and forward an inclined front framework 13, against the inner side or surface of which abut the inclined wall-like extensions 10 of the floors 9. The lower and 80 front portion of the frame 13 connects, as shown, with the upper side of the forward wall 2. The ends of the structure thus formed may be closed by end walls, a portion of one of which is shown at 14, and suitable transverse partitions may be arranged at intervals, said partitions intersecting the horizontal compartments which are formed between the pairs of floors 9 and, if desirable, intersecting the passages 8.

In the front frame 13 I provide openings which may be filled, as shown in Fig. 1 of the drawings, with glass-filled frames 15, these glass-filled openings being at the end of the forward and upwardly-inclined portions of 90 the compartments, which are formed between the inclined floor extensions 10. It will be

observed that each of the passages or hallways 8 has its upper portion leading directly into one of the compartments, and owing to the fact that the lower termination of said 5 passage is below the floor of the compartment with which it communicates the passage is provided with desirable head-room without the necessity of increasing the height of the compartment with which it communicates.

10 In Fig. 2 of the drawings I have shown a modification of this passage construction, which consists in forming the passages, which in said figure are indicated at 8^a, angular in cross-section and providing for a communication of the rear ends of three compartments, such as are indicated at 8^b, with each of said angular passages.

It is obvious that entrance to the various compartments may be gained through doors 20 connecting with the passages or hallways. It will also be understood that through the medium of the glass-covered openings which are provided for the forward sides of the compartments light will be provided for each of 25 said compartments, and in this connection it may be stated that when considered desirable the inclined ends of the compartments formed by the inclined floor terminations 10 may be in the nature of horizontal extensions of said 30 compartments instead of inclined extensions, as shown, although it is obvious that a greater height may be attained in the forward portion of each of said compartments by the employment of the inclined terminations.

35 From the construction shown and described it will be seen that not only may a hillside be employed as a building site, but that a compact arrangement of well-lighted compartments is attained by the utilization 40 of a comparatively small area of ground and less than the usual amount of vertical space.

While the building construction herein shown is particularly adapted to be used as a chicken-house for raising chickens in large 45 quantities or as a greenhouse for raising plants, it is obvious that the same may be utilized for other purposes.

Having now fully described my invention,

what I claim, and desire to secure by Letters Patent, is—

1. In an inclined building construction, the combination with a horizontally-disposed compartment, of a series of compartments arranged one above the other, the fronts of said compartments following an incline and supports for said compartments on different elevations. 55

2. In an inclined building construction, the combination with a series of compartments arranged one above the other on an incline, 60 said compartments having supports at different elevations and an inclined roof-supporting framework covering the fronts of said compartments, substantially as specified.

3. In an inclined building construction, the 65 combination with a series of compartments arranged one above the other on a hillside, said compartments having supports from the hillside at points in rear of each other and at different elevations and an inclined glass-containing framework covering the fronts of 70 said compartments, substantially as specified.

4. In an inclined building construction, the combination with a series of compartments arranged one above the other, and having 75 supports at different elevations and a passage-way in the rear of each of said compartments excepting the top and bottom compartments, each of said passage-ways being of greater height than the height of the compartment with which it communicates, the 80 ceilings of said passage-ways being formed by the floors of the next higher compartments, substantially as specified.

5. In an inclined building construction, the 85 combination with a series of compartments arranged one above the other, each of said compartments having its forward end portion inclined upwardly and an inclined glass-containing framework covering the forward ends 90 of said compartments.

GERARD C. SCOTT.
